UNITED STATES PATENT OFFICE.

FRED E. KEIZER, OF LOS ANGELES, CALIFORNIA.

SAFETY ATTACHMENT FOR LOCKS.

1,277,221.

Specification of Letters Patent. Patented Aug. 27, 1918.

Application filed April 4, 1918. Serial No. 226,726.

To all whom it may concern:

Be it known that I, FRED E. KEIZER, a citizen of the United States, residing at Los Angeles, in the county of Los Angeles and 5 State of California, have invented new and useful Improvements in Safety Attachments for Locks, of which the following is a specification.

My invention relates to locks, my object 10 being to make a safety attachment which may be readily applied to an ordinary door lock to reduce the liability of the lock being picked from the outside, and my invention consists in the novel features herein shown, 15 described and claimed.

Figure 1 is a fragmentary perspective of the lock and a portion of the door as seen from the inside.

Fig. 2 is a view analogous to Fig. 1, the 20 parts being shown as seen from the outside of the door.

Fig. 3 is an enlarged fragmentary edge view of the door in the vicinity of the lock, parts of the door and lock being broken 25 away and shown in section.

Fig. 4 is a side and end elevation of the attachment cylinder removed from the door.

The mortise lock 1 is mounted in the door 2 in the usual way and has an escutcheon 30 plate 3 and a knob 4 on the inside of the door and an escutcheon plate 5 and a knob 6 on the outside of the door. In applying 35 my safety attachment, I take the regular key 7 and cut a tongue groove 8 across its inner end. The attachment cylinder 9 has an attaching flange 10 extending outwardly around its outer end and screw holes 11 through flange 10. I remove the escutcheon 40 plate 5, bore a cylinder chamber 12 from the outer face of the door in line with the key 7, place the cylinder 9 with the flange 10 against the inner face of the escutcheon, place the keyhole plate 13 against the escutcheon plate 5 and insert the screws 14 through 45 the key hole plate 13, through the escutcheon plate 5, and through the holes 11 in the flange and apply the nuts, and then place the escutcheon plate 5 in position upon the door. The connecting plate 15 is mounted 50 in the inner end of the cylinder 9 to be rotated by the rotation of the cylinder key 16. A tongue 17 extends from the inner face of the connecting plate 15 to fit in the groove 8 in the key 7. The casing 18 of the cylinder 9 is rigidly fixed relative to the connect-

ing plate 15 and a tooth 19 extends from the casing and engages shoulders 20 and 21 upon the connecting plate 15, so as to limit the rotation or oscillation back and forth of the plate.

The periphery of the plate 15 is cut away to the line 22 between the shoulder 20 and 60 21 to make a clearance for the tooth 19. In making the tongue groove 8 and the tongue 17 and the shoulders 20 and 21, and in locating the tooth 19, the key 7 is to be set in the lock 1 so that it will oscillate back and forth to operate the bolt 23 and so that the key cannot be withdrawn from the lock. In other words, the key 7 is inserted into the 65 key hole 24 and turned until it starts to move the bolt 23 and that is the fixed position for setting the cylinder 9 so that when the key 16 or the key 7 is rotated backwardly, the shoulder 21 will strike the tooth 70 19 before the tongue of the key 7 reaches the slot 24 and so that when either key is turned the other way, the shoulder 20 will strike the tooth 19 and prevent the key 7 from turning over to the slot 24. At the 75 same time, the parts are set so that the key slot 25 for the key 16 will be in the proper position to withdraw or insert the key, as is usual. The cylinder 9 and key 16 may be of any form or construction which will 80 rotate the connecting plate 15 with the proper key and which cannot be rotated in any other way.

Various changes in the combination and arrangement of parts may be made without 85 departing from the spirit of my invention 90 as claimed.

I claim:

1. The combination with a door, a mortise lock in the door, an escutcheon plate on the 95 outdoor side of the door; there being a key hole extending through the door and through the mortise lock; and a key inserted through the key hole into the mortise lock from the indoor side; there being a tongue groove in 100 the inner end of the key; of a safety attachment comprising an escutcheon cylinder mounted in the outer face of the door in line with the key hole, an attaching flange extending outwardly around the escutcheon 105 cylinder, bolts securing the attaching flange against the inner face of the escutcheon plate, a key cylinder in the escutcheon cylinder, a connecting plate rotatably mounted in the inner end of the escutcheon cylinder to 110

rotate with the key cylinder, and a tongue extending from the connecting plate into the groove in the key.

2. The combination with a door, a mortise lock in the door, an escutcheon plate on the outdoor side of the door; there being a key hole extending through the door and through the mortise lock; and a key inserted through the key hole into the mortise lock from the indoor side; there being a tongue groove in the inner end of the key; of a safety attachment comprising an escutcheon cylinder mounted in the outer face of the door in line with the key hole,

an attaching flange extending outwardly around the escutcheon cylinder, bolts securing the attaching flange against the inner face of the escutcheon plate, a key cylinder in the escutcheon cylinder, a connecting plate rotatably mounted in the inner end of the escutcheon cylinder to rotate with the key cylinder, and a tongue extending from the connecting plate into the groove in the key; the parts being set so that the key cannot be removed from the mortise lock. 25

In testimony whereof I have signed my name to this specification.

FRED E. KEIZER.
